(57) **CLAIM**

The ornamental design for a urine deflector, as shown and described.

DESCRIPTION

FIG. 1 is a right, front, and bottom perspective view of a urine deflector, depicting the use thereof;

FIG. 2 is a left, rear, and top perspective view thereof;

FIG. 3 is a right, front, and bottom perspective view thereof;

FIG. 4 is a left side elevational view thereof, the opposite side being a mirror image;

FIG. 5 is front elevational view thereof;

FIG. 6 is a rear elevational view thereof;

FIG. 7 is a top plan view thereof; and,

FIG. 8 is a bottom plan view thereof.

The broken lines in the drawings illustrate a toilet and forms no part of the claimed design.
